MOISTENER FOR DUPLICATING MACHINES

Stephen Kokay, Chicago, Ill., assignor to Ditto,
Incorporated, Chicago, Ill., a corporation of
West Virginia

Application January 10, 1936, Serial No. 58,522

9 Claims. (Cl. 101—132)

This invention relates to duplicating machines of the general type shown in the application of John W. Hernlund, Serial Number 44,911 filed October 14, 1935, for a Duplicating machine.

5 Machines of this type employ master sheets which are mounted upon a drum and copy sheets are moistened with a suitable solvent for the ink or carbon on the master sheet immediately before it is brought into contact with the side of 10 the master sheet upon which the ink or carbon is placed. The master sheets have the data to be duplicated formed thereon in reverse so that when a portion of the carbon or ink is dissolved off and transferred to the moistened surface of 15 the copy sheet it will appear in correct readable form. In practice, some readily volatile solvent such as alcohol is employed.

One form of the invention is embodied in a machine of the type described in the aforesaid 20 application which machine comprises a rotary drum having means for clamping master sheets thereto. The copy sheets may be advanced to the drum in any suitable manner such, for example, as by means of a pair of feed rollers. A 25 platen roller is employed to press the copy sheets against the master sheet for transferring the data on the master sheet to a copy sheet. One of the feed rollers may desirably constitute a moistening roller so that one surface of the copy 30 sheet is moistened as it is fed to the drum. The improved machine embodying the present invention comprises a moistening receptacle adapted to receive moistening fluid from a suitable source of supply. This receptacle contains means for 35 distributing the moistening fluid throughout the receptacle and contains a body of absorbent material which projects from the container to engage the moistening roller. The improved machine preferably includes means for isolating a 40 portion of the absorbent material from the moistening liquid so that a portion only of the moistening roller will be moistened when, for example, the copy sheets being applied are narrower than the full length of the moistening roller or 45 when, for any reason, it is desirable to take off only a portion of the data upon the master sheet.

The improved machine also comprises a novel 50 mounting means for the moistening receptacle, whereby correct application of pressure between the absorbent material and the moistening roller may be obtained.

Other features and advantages of the invention 55 will become apparent as the following descrip-

tion progresses, reference being had to the accompanying drawings, wherein—

Fig. 1 is a plan view of a duplicating machine which embodies the invention.

Fig. 2 is a sectional view on the line 2—2 of 5 Fig. 1.

Fig. 3 is a sectional view of a portion of the mechanism taken horizontally over the moistening receptacle, certain parts being broken away for the sake of clearness. 10

Fig. 4 is a sectional view on the line 4—4 of Fig. 3.

Fig. 5 is a sectional view on the line 5—5 of Fig. 3.

Fig. 6 is a sectional view on the line 6—6 of 15 Fig. 5.

Fig. 7 is a fragmentary front elevation of a portion of the moistening receptacle.

Fig. 8 is a sectional view on the line 8—8 of Fig. 4. 20

Fig. 9 is a sectional view of a portion of the mechanism shown in Fig. 8 showing a changed position, and

Fig. 10 is a view in perspective of the absorbent device used in the receptacle, illustrating a modified form in which the absorbent strip is not divided transversely. 25

Referring now to the drawings in which a preferred embodiment of the invention is shown, the reference characters 11 and 12 designate a pair 30 of side frames adapted to rest upon any suitable support, the side frames being provided with suitable rubber feet as indicated at 13. The side frames 11 and 12 are secured together by any suitable means, such as brackets 14 and 15. 35 The machine further embodies a drive motor 16 and suitable mechanism including a belt 17, a pulley 18, a pulley 19, a belt 19', a pulley 20, a pinion 21 fixed to the pulley 20 and a gear 22 for supplying driving power for the machine. A 40 drum 23 is supported upon a shaft 24 which is rotatably journaled in the side frames 11 and 12. Suitable mechanism comprising a ratchet wheel 25 and a pawl 26 are adapted to connect the drum 23 to the gear 22 for purposes of imparting rotation to the drum. This connection is controlled by a suitable trip lever mechanism indicated generally at 27 and a cross bar 28 as more fully described in the aforesaid application. 45

The machine further comprises a copy sheet table 29 upon which copy sheets are laid to be fed to the drum. A receiving tray 30 is provided and a master sheet tray 31 is also provided for supplying master sheets to the drum 23. A 50 55

platen roller 32 is adapted to press copy sheets against a master sheet upon the drum.

A liquid supply container 33 is suitably supported by the brackets 14 and 15 and carries a pump 34 adapted to be actuated by a bell crank lever 35 from a cam 36 fixed to the drum 23. Liquid is supplied from the container 33 to a moistening receptacle 37 through a conduit 38 having a vent chamber 39 therein. The volatile liquid used in machines of this character is supplied from the receptacle 37 through an absorbent wick 40 to a combined feeding and moistening roller 41 which is driven from the drum 23 by means of a main gear 42 on the drum, an idler gear 43 and a drive gear 44 fixed to the roller 41. The roller 45 co-operates with the roller 41 to feed copy sheets such as 46 to the drum 23. The roller 45 has a felt covering 47 to absorb excess moisture from the feed roller 41.

20 The copy sheet table 29 has a guide plate 48 thereon, which guide plate extends upwardly toward the junction of the rollers 41 and 45 and has a flat portion 49 which terminates as close as is practical to the junction of the rollers. The 25 moistening receptacle 37 has a lip at 50 which is spaced slightly above the portion 49 so as to provide a restricted guideway for directing sheets to the rollers 41 and 47.

The present invention concerns itself primarily with the moistening receptacle 37, the absorbent member 40 and the means for supplying liquid from the conduit 38 to the absorbent member 40. It will be noted from an inspection of Figs. 3 and 4, in particular, that the conduit 38 35 enters the receptacle 37 at one end thereof and extends substantially to the center of the receptacle to a valve housing 51. The valve housing 51 is provided with a recess 52 around the inner end of a nipple 53 that connects the conduit 38 40 to the housing 51. An opening 54 provides for passage of liquid from within the nipple to the recess 52. A valve 55 is mounted to rotate in the wall of the receptacle 37 by a reduced portion 56. A further reduced portion 57 of the 45 valve is adapted to receive a valve operating handle and indicator 58 which is held upon the portion 57 between two washers 59 and 60 by a screw 61. At its inner end, the valve 55 has a reduced portion 62 on which the washers 63 fit. 50 The washers 63 are yieldingly pressed against the housing 51 by a spring 64 which is held in place by a screw 65.

The housing 51 is provided with a cylindrical bore to receive the valve 55 which has a port 66 55 therein, which port may be aligned with two openings 67 and 68 leading from the recess 52 into the bore provided in the housing for the valve 55. The housing is also provided with outlet openings 69 and 70 from the port 66, which openings 60 are directed into a pair of recesses 71 and 72 provided in the housing 51. These recesses have mounted therein a pair of distributing pipes 73 and 74 adapted to distribute the moistening liquid lengthwise of the receptacle 37. As shown 65 most clearly in Fig. 8, the pipes 73 and 74 are provided with suitable apertures 75 adapted to direct the liquid against the back wall of the receptacle 37. The outer ends of the pipes 73 and 74 are plugged and may be secured to the ends of 70 the receptacle 37 in any suitable manner such, for example, as by means of a plug 76 and a screw 77 (Fig. 6). Beneath the pipes 73 and 74 the receptacle is provided with one or more shelf portions 78 which are adapted to support a rear edge 79 of the absorbent element 40. A drain

outlet 70 is also provided for removing excess liquid from beneath the absorbent element 40. The element 40 lies substantially flat in the receptacle 37 sloping downwardly slightly toward the roller 41 and it rests upon a shoulder 81 5 provided on the receptacle directly beneath an opening 82 through which the absorbent element 40 projects to engage the roller 41. This element 40 is turned downward to engage the top surface of the lip 50 and is doubled upon itself to provide a thick body of absorbent material which can be pressed against the roller 41. The free edge of the element 40 is extended upwardly and fastened to the outside of the wall of the receptacle 37 by means of a bar 83 and suitable screws 15 74. The pressure of the bar 83 upon the absorbent element controls to a certain extent the flow of moisture to the roller 41. This pressure may be varied by adjusting the screws 74. A cover 75 is provided for the receptacle. 20

The receptacle 37 is preferably so mounted in the side frames 11 and 12 as to be yieldingly urged toward the roller 41 at all times. The details of this mounting are shown best in Figs. 3 and 6. At one end the receptacle 37 is secured to the side frame 12 by a stud 86 in which a projection 87, fixed in the end of the receptacle, is journaled. At the other end of the receptacle 37, a plate 88 is mounted by means of a rivet 89 and a combined rivet and bearing member 90. The member 90 has a flange 91 thereon adapted to abut the end of a stud 92 fixed in the side frame member 11 and has further a projection 93 journaled in a recess 94 in the member 92. The plate 88 is curved away from the end of the receptacle 37 at the top and projects upwardly above the receptacle as indicated at 95 to engage a pin 96 upon a bell crank lever 97. The bell crank lever 97 is pivoted upon the member 92 and has an arm 98 projecting horizontally. A pin 99 is fixed in the side frame 11 and projects outwardly over the arm 98 as shown most clearly in Fig. 3 to provide a stop limiting the movement of the arm 98 in a counterclockwise direction.

A coiled spring 100 is mounted on an extended hub portion 101 of the bell crank lever 97. This spring has one end 102 fixed to the pin 99 while the other end 103 is hooked over the bell crank lever 97. Thus, the spring continuously urges the bell crank lever in a direction to press against the upper portion 95 of the plate 88 so as to tend to turn the receptacle 37 about its pivot members 87 and 93 and press the member 40 against the roller 41.

As illustrated best by Figs. 8 and 9, the valve 55 may be adjusted to supply liquid to either one or both of the pipes 73 and 74 and it may be turned in such a position as to supply more liquid to one of the pipes than to the other as will be readily understood. In addition, the member 40 is divided in its horizontal portion by a slot 104 (Figure 3) so that the moistening liquid can not spread from one section to the other when the valve 55 has cut off the supply to one section. Thus, it is possible to eliminate the supply of liquid to one of the pipes 73 or 74 when the narrow copy sheets are being moistened. This results in considerable economy in the use of liquid and further prevents overcharging of the felt covering 47 on the roller 41. 70

While certain embodiments of the invention have been shown and described, it is to be understood that it is capable of many modifications. Changes, therefore, in the construction and arrangement may be made without departing from 75

the spirit and scope of the invention as disclosed in the appended claims in which it is the intention to claim all novelty inherent in the invention as broadly as possible in view of the prior art.

5 Having thus described the invention, what I claim as new and desire to secure by Letters Patent is:

1. In a duplicating machine, a drum, means to mount a master sheet thereon, means to press 10 copy sheets against said master sheet, and a moistening device for moistening the copy sheets as they are advanced to said drum, said moistening device comprising a moistening roller adjacent to and substantially parallel with said drum, a 15 moistening fluid receptacle, an absorbent element protruding from said receptacle and engaging said roller, and liquid supply means for said absorbent element comprising means for selectively wetting separate sections of said absorbent element, said absorbent element having means to restrict the spread of liquid lengthwise therein.

2. In a duplicating machine of the character described, moistening means comprising a moistening receptacle, absorbent means in said receptacle and projecting from said receptacle for delivering moistening liquid to an applicator for moistening sheets, an applicator, and means to selectively restrict supply of moistening liquid to different portions of said applicator, said last 30 named means comprising a plurality of liquid spreading devices in said receptacle, each adapted to supply liquid to a particular section of said absorbent means, and said absorbent means having the sections thereof substantially isolated 35 from each other within said receptacle.

3. In a duplicating machine of the character described, a moistening receptacle having a shelf portion at one side thereof and having an opening at the other side, an absorbent element supported 40 on said shelf portion said element extending across the receptacle and projecting into said opening, and means to deliver moistening liquid onto said element within the receptacle, said receptacle having a space beneath said element and 45 between the shelf and the opening to receive excess liquid from said element.

4. In a duplicating machine of the character described, a moistening receptacle having a shelf portion and having an opening at one side, an absorbent element supported on said shelf portion and projecting into said opening, and means to deliver moistening liquid onto said element within the receptacle, said receptacle having a space beneath said element to receive excess liquid from 50 said element, said receptacle having an exterior lip beneath said opening, and said element having a doubled portion overlying said lip.

5. In a duplicating machine of the character described, a moistening receptacle having a shelf portion at one side thereof and having an opening at the other side, an absorbent element supported 60 on said shelf portion said element extending across the receptacle and projecting into said opening, and means to deliver moistening liquid onto 65 said element within the receptacle, said receptacle having a space beneath said element and between the shelf and the opening to receive excess liquid from said element, the portion of said

absorbent element within the receptacle being divided transversely of the receptacle.

6. In a duplicating machine of the character described, a moistening receptacle having a shelf portion and having an opening at one side, an absorbent element supported on said shelf portion and projecting into said opening, and means to deliver moistening liquid onto said element within the receptacle, said receptacle having a space beneath said element to receive excess liquid from 10 said element, said receptacle having an exterior lip beneath said opening, and said element having a doubled portion overlying said lip, and clamping means for clamping the free edge of said element to the exterior of the receptacle above said 15 opening.

7. A duplicating machine comprising a frame, a drum rotatably journaled therein, means to mount a master sheet on said drum, a copy sheet table adjacent to said drum, combined feeding 20 and moistening rollers adapted to advance copy sheets fed thereto to said drum and to moisten one surface of the advancing copy sheet, and a moistening device for supplying moistening fluid to one of said rollers, said moistening device comprising a receptacle pivotally supported by said frame along side the roller to be moistened, absorbent means projecting through the wall of said receptacle to engage said roller, means within said receptacle for supplying liquid to said absorbent means, and spring means urging said receptacle toward said roller, said absorbent means having a doubled portion outside the receptacle to engage said roller, and the free end portion of 30 said absorbent means being clamped against said 35 receptacle.

8. In a duplicating machine of the character described, moistening means comprising a moistening receptacle, sections of absorbent means in said receptacle and projecting therefrom, an applicator contacted by said sections for receiving moistening fluid therefrom, and means in said receptacle for selectively supplying moistening liquid to said sections, said sections being spaced from each other and said applicator being adapted 40 to contact copy sheets to moisten them.

9. In a duplicating machine of the character described, a frame, a drum rotatably journaled therein, means to mount a master sheet on said drum, a copy sheet table adjacent said drum, 50 combined feeding and moistening rollers adapted to advance copy sheets fed thereto to said drum and to moisten one surface of each advanced copy sheet, and a moistening device for supplying moistening fluid to one of said rollers, said 55 moistening device comprising a receptacle pivotally supported by said frame adjacent the roller to be moistened, sections of absorbent means in said receptacle and projecting therefrom, said sections contacting said roller to be supplied with 60 moistening fluid, yielding means for urging said receptacle in a direction to urge said sections against the last-mentioned roller, and means in said receptacle for selectively supplying moistening fluid to said sections, said sections being 65 spaced from each other.

STEPHEN KOKAY.
